DRILL CUTTER

Henry Rogatz, Sayre, Okla., assignor to Phillips
Petroleum Company, Bartlesville, Okla., a corporation of Delaware

Application December 30, 1933, Serial No. 704,686

15 Claims. (Cl. 255—71)

This invention relates to an improved type of cutters for roller boring drills.

It has often been found that in drilling wells, particularly oil and gas wells, many hard formations are encountered, such as granite wash and similar hard formations. In rotary drilling operations, hard formation bits are usually used to drill through hard formations; particularly granite wash, which consists of individual grains or fragments of granite imbedded in a solid formation which is not so hard as granite. The customary type of cutters used in such drilling have sharpened wedge shaped teeth that intermesh as the cutters rotate, creating a cutting, and to some extent a crushing, effect upon the formation at the bearing surface of the bit.

I have discovered that cutters, having flattened teeth, provide a more efficient crushing action than cutters having sharpened or wedge shaped teeth.

Advantages of this invention over drill cutters of the conventional type are, longer life for drill bits, faster drilling, fewer replacements and changes, more sturdy construction with less breaking of teeth and savings in time ordinarily consumed in taking out bits to be rebuilt.

The primary object of this invention, which provides cutters with flat edged teeth, is to effect a more thorough crushing action on formations through which a hole is being drilled.

Although the teeth of the cutters described in this invention could be alternately flattened and wedge shaped, the preferred embodiment comprises cutters having all teeth with flattened points and having tapered sides to prevent clogging.

In the event formations are encountered that require more cutting than crushing action, the more suitable type of cutters would be those having alternating wedge shaped and flattened teeth. The alternating type of cutters would be particularly well adapted for use in drilling through a solid hard formation, the knife edged or wedge shaped teeth functioning to cut or break up the formation and, the blunt, flat edged teeth to complete the crushing action necessary to prepare the well cuttings for removal.

The foregoing objects of this invention will be further described in detail and the novel features thereof disclosed more fully as the description proceeds, with the aid of the accompanying drawings and appended claims.

Referring now to the drawings:—

55 Figure 1 is a sectional top view of a cutter

having alternating flat edged and sharp edged teeth.

Figure 2 is a portional side view of the cutter shown in Figure 1 and showing the longitudinal rows of flat edged teeth alternating with the 5 longitudinal rows of sharp edged teeth, all having tapered sides.

Figure 3 is a sectional top view of a cutter having all flat edged teeth with tapering sides.

Figure 4 is a sectional top view of a cutter 10 having circumferential rows of flat edged teeth alternating with circumferential rows of sharp edged teeth.

Figure 5 is a portional side view of a cutter having all flat edged teeth with tapering sides. 15

Figure 6 is a portional side view of a cutter showing circumferential rows of flat edged teeth alternating with circumferential rows of sharp 20 edged teeth, all having tapering sides.

Figure 7 is a sectional top view of a cutter 25 having alternating flat edged and sharp edged teeth with tapering sides.

Figure 8 is a portional side view of the cutter shown in Figure 7, showing the flat edged teeth alternating diagonally with the sharp edged 30 teeth, all having tapering sides.

Figure 9 is a view of the cutter in its position in a rotary drill bit.

With particular reference to the drawings, 35 wherein like reference characters indicate corresponding parts, the letter X designates a portion of the body of a drill cutter, and Figure 1 shows a top view of the portion X showing the arrangement thereon of alternating flat and sharp 40 edged teeth spaced apart so as to permit intermeshing with other cutters. Another view of these alternating flat edged teeth A, and sharp edged teeth B, shown in Figure 2, shows the tapering sides of the teeth and spaces C into which the other cutters fit and intermesh as the cutters rotate. The cutter shown in Figure 1 and Figure 2, shows the flat edged teeth in longitudinal rows alternating with sharp edged teeth in longitudinal rows. The cutter shown in Figure 4 and Figure 6 shows flat edged teeth A in 45 circumferential rows alternating with sharp edged teeth B in circumferential rows, all having tapering sides. The cutter shown in Figure 3 and Figure 5 shows all flat edged teeth with 50 tapering sides. The cutter shown in Figure 7 and Figure 8 shows flat edged teeth alternating diagonally with sharp edged teeth with spaces C into which the corresponding teeth of other cutters fit as the cutters rotate.

As an example to show the application of my 55

new type of cutters to the drilling of a granite wash formation, the drill bit is utilized, as shown in Figure 9 of the drawings, which is a conventional type of rotary drill bit. For drilling 5 through such a formation, cutters, as shown in Figure 3 and Figure 5 on which are mounted flat edged teeth A, are attached to the bit in the conventional manner. I have found that drilling, through this type of formation is 10 greatly expedited by an action which crushes the hard granite surfaces rather than by an action which attempts to cut such hard surfaces, since it has been found heretofore that cutters having sharp edged teeth are quickly 15 destroyed. In actual experience it has been found that sharp edged cutters must be replaced or rebuilt about every five feet whereas the flat edged teeth of my invention insures a more efficient crushing action and may be used in 20 drilling from 10 to 15 feet without replacement. Likewise, in drilling with cutters having sharp edged teeth, it requires about 12 hours to drill 8 feet; whereas, by the use of my cutters having flat teeth, only 12 hours are required to drill 25 from 16 to 24 feet.

In formations of varying hardness it may be found preferable to employ a bit having several cones, one or more of which may have mounted thereon cutting teeth with wedge shaped edges, 30 the others having mounted thereon cutting teeth with flat surfaces or any combination of arrangement of teeth described above.

I do not desire to be limited by the shape or size of teeth in my cutters nor to the shape or 35 size of cutters except insofar as I may be limited by the scope of the appended claims.

Having thus described my invention, what I claim is:

1. A frusto-conical drilling tool having a cone 40 shaped cutting area provided with a plurality of axially aligned rows of cutting teeth alternate teeth having cutting surfaces terminating in either a flat top grinding surface or a sharp top cutting edge, and a plurality of axially 45 aligned non-cutting surfaces disposed upon said cone between the rows of said cutting teeth.

2. A frusto-conically shaped drilling tool having a cone shaped cutting area, a plurality of cutting teeth mounted on said area terminating 50 in flat top cutting surfaces, and a plurality of additional teeth terminating in sharp cutting edges arranged upon said cone in alternate relation with respect to said first teeth mentioned.

3. A frusto-conical drilling tool having a cone 55 shaped cutting area provided with a plurality of axially aligned rows of cutting teeth, alternate teeth having cutting surfaces terminating in a flat top grinding surface, and a plurality of axially aligned non-cutting surfaces disposed 60 upon said cone between the rows of said cutting teeth.

4. A frusto-conical drilling tool having a cone 65 shaped area provided with a plurality of axially aligned rows of cutting teeth, alternate teeth having cutting surfaces terminating in a sharp top cutting edge, and a plurality of axially aligned non-cutting surfaces disposed upon said 70 cone between the rows of said cutting teeth.

5. A frusto-conical drilling tool having a cone 75 shaped cutting area provided with a plurality of circumferentially aligned rows of cutting teeth, alternate teeth having cutting surfaces terminating in either a flat top grinding surface or a sharp top cutting edge, and a plurality of circumferentially aligned non-cutting

surfaces disposed upon said cone between the rows of said cutting teeth.

6. A frusto-conical drilling tool having a cone shaped cutting area provided with a plurality of axially aligned rows of cutting teeth, alternate teeth having cutting surfaces terminating in either a flat top grinding surface or a sharp top cutting edge, and a plurality of circumferentially aligned non-cutting surfaces disposed upon said cone between the rows of cutting teeth. 10

7. A frusto-conical drilling tool having a cone shaped cutting area provided with a plurality of axially aligned rows of cutting teeth, alternate teeth having cutting surfaces terminating in a flat top grinding surface, and a plurality of circumferentially aligned non-cutting surfaces disposed upon said cone between the rows of cutting teeth. 15

8. A frusto-conical drilling tool having a cone shaped area provided with a plurality of axially aligned rows of cutting teeth, alternate teeth having cutting surfaces terminating in a sharp top cutting edge, and a plurality of circumferentially aligned non-cutting surfaces disposed 20 upon said cone between the rows of cutting teeth. 25

9. A frusto-conically shaped drilling tool having a cone shaped cutting area, a plurality of cutting teeth mounted on said cone and including teeth terminating in flat top cutting surfaces and teeth terminating in sharp cutting edges. 30

10. A frusto-conically shaped drilling tool having a cone shaped cutting area, a plurality of cutting teeth mounted on said area terminating in flat top cutting surfaces, and a plurality of additional teeth terminating in sharp cutting edges arranged upon said cone in alignment with respect to said first mentioned teeth. 35

11. A frusto-conically shaped drilling tool having a cone shaped cutting area, a plurality of cutting teeth mounted on said area terminating in flat top cutting surfaces, and a plurality of additional teeth terminating in sharp cutting edges arranged upon said cone in spaced relation with respect to said first mentioned teeth and separated therefrom by a plurality of axially aligned non-cutting surfaces disposed between 40 said teeth. 45

12. A frusto-conically shaped drilling tool having a cone shaped cutting area, a plurality of cutting teeth mounted on said area terminating in flat top cutting surfaces, and a plurality of additional teeth terminated in sharp cutting edges arranged upon said cone in spaced relation with respect to said first mentioned teeth and separated therefrom by a plurality of circumferentially aligned non-cutting surfaces disposed 50 between said teeth. 55

13. A frusto-conically shaped drilling tool having a cone shaped cutting area, a plurality of cutting teeth mounted on said area terminating in flat top cutting surfaces, a plurality of additional teeth terminating in sharp cutting edges, arranged upon said cone in alternate relation with respect to said first mentioned teeth, and axially and circumferentially aligned non-cutting areas disposed between the said teeth terminating in flat top cutting surfaces and the said teeth terminating in sharp cutting 60 edges. 65

14. A frusto-conically shaped drilling tool having a cone shaped cutting area, a plurality of cutting teeth mounted on said area terminating in flat top cutting surfaces, a plurality of addi- 70 75

5 tional teeth terminating in sharp cutting edges arranged upon said cone in alternate relation with respect to said first mentioned teeth, and axially aligned non-cutting areas disposed between the said teeth terminating in flat top cutting surfaces and the said teeth terminating in sharp cutting edges.

10 15. A frusto-conically shaped drilling tool having a cone shaped cutting area, a plurality of cutting teeth mounted on said area terminating

in flat top cutting surfaces, a plurality of additional teeth terminating in sharp cutting edges arranged upon said cone in alternate relation with respect to said first mentioned teeth, and circumferentially aligned non-cutting areas disposed between the said teeth terminating in flat top cutting surfaces and the said teeth terminating in sharp cutting edges.
